(57) **CLAIM**

The ornamental design for a bowl, as shown and described.

DESCRIPTION

FIG. 1 is a top, front perspective of a bowl showing our new design;
FIG. 2 is a bottom, front perspective view thereof;
FIG. 3 is a front view thereof;
FIG. 4 is a rear view thereof;
FIG. 5 is a right side view thereof;
FIG. 6 is a left side view thereof;
FIG. 7 is a top view thereof;
FIG. 8 is a bottom view thereof; and,
FIG. 9 is a top, front perspective view of an alternative claimed configuration of a bowl showing our new design.
